FIG. 1 is a perspective view of a present invention high definition door skin with soft arch;
FIG. 2 is a front elevational view of the present invention high definition door skin with soft arch;
FIG. 3 is a right side view of the present invention high definition door skin with soft arch;
FIG. 4 is a top plan view of the present invention high definition door skin with soft arch;
FIG. 5 is a bottom plan view of the present invention high definition door skin with soft arch;
FIG. 6 is a cross-sectional view of the invention taken generally along line 6—6 in FIG. 2;
FIG. 7 is a cross-sectional view of the invention taken generally along line 7—7 in FIG. 2; and,
FIG. 8 is a cross-sectional view of the invention taken generally along line 8—8 in FIG. 2.

A left side view has been omitted since it is a mirror image of the right side view.
